US00D609544S

(12) **United States Design Patent**
Lopano et al.

(10) **Patent No.:** **US D609,544 S**
(45) **Date of Patent:** **** Feb. 9, 2010**

(54) **DRILL DRIVER**

(75) Inventors: **Daniel N. Lopano**, Bel Air, MD (US);
Gabriel E. Concari, Eldersburg, MD
(US); **Sion Netzler**, Abingdon, MD (US)

CH 386808 4/1965

(73) Assignee: **Black & Decker, Inc.**, Newark, DE (US)

(Continued)

(**) Term: **14 Years**

(21) Appl. No.: **29/332,734**

(22) Filed: **Feb. 24, 2009**

(51) **LOC (9) Cl.** **08-04**

(52) **U.S. Cl.** **D8/68**

(58) **Field of Classification Search** D8/14.1,
D8/61, 62, 63, 64, 65, 66, 67, 68, 69, 70;
81/57.11, 429, 454, 455, 456, 469, 489; 173/13,
173/104, 114, 168, 169, 170, 171, 178, 201,
173/211, 213, 217; 408/20, 124, 125, 234,
408/241 R; 451/358; 310/50; 227/8, 113,
227/114, 120, 130, 136, 142

See application file for complete search history.

(57) **CLAIM**

The ornamental design for a drill driver, as shown and described.

DESCRIPTION

FIG. 1 is a perspective view of the a drill driver.

FIG. 2 is a front view of the drill driver.

FIG. 3 is a rear view of the drill driver.

FIG. 4 is a left view of the drill driver.

FIG. 5 is a right view of the drill driver.

FIG. 6 is a top view of the drill driver; and,

FIG. 7 is a bottom view of the drill driver.

The portions in broken lines do not form any part of the claimed design.

1 Claim, 5 Drawing Sheets

US D609,544 S
